YARN FINGER FOR KNITTING MACHINES

Ivan W. Grothey, Laconia, N. H., assignor to
 Scott & Williams, Incorporated, New York,
 N. Y., a corporation of Massachusetts

Application March 5, 1935, Serial No. 9,483

11 Claims. (Cl. 66—133)

This invention relates to knitting machines and more particularly to the yarn fingers or guides which feed the yarns to the needles and it is an object of this invention to provide a yarn finger and an operating means therefor which will insure the yarn fed by the yarn guide being taken by a predetermined needle and fed only to predetermined needles where the yarn is fed to the needles for a portion of each course during a number of successive courses as in feeding a splicing or reinforcing yarn in the knitting of a high splice or a reinforced sole. It is also an object of this invention to provide a yarn finger which, in introducing a yarn to the needles, is lowered to a position close to the needles to insure the yarn being taken by the leading needle to which the yarn is to be fed and is then moved away from the needles in order to feed the yarn to the needles at the proper angle to insure the yarn taking its proper position in relation to other yarn or yarns being fed to the needles at the same time. It is also an object of this invention to provide a yarn finger which, in withdrawing a yarn from the needles, is first moved towards the needles and then raised from the needles so as to insure the yarn being withdrawn at the predetermined needle.

In the drawing which illustrates the preferred form of this invention—

Fig. 1 is a perspective view of a yarn finger and its operating means which are constructed in accordance with this invention showing the parts separated and detached from the latch ring;

Fig. 2 is a perspective view of the parts shown in Fig. 1 assembled in normal relation;

Fig. 3 is a sectional view of the latch ring showing in side elevation the yarn finger of Fig. 1 in position to introduce its yarn to the needles all but one yarn finger being omitted;

Fig. 4 is a view similar to Fig. 3 showing the position of the yarn finger after the yarn has been taken by the needles and the yarn finger moved back from the needles;

Fig. 5 is a view similar to Fig. 3 showing the yarn finger raised and the yarn withdrawn from the needles;

Fig. 6 is a fragmentary view of the latch ring of Fig. 3 showing the yarn fingers in front elevation and with the yarn finger constructed in accordance with this invention in the position shown in Fig. 3;

Fig. 7 is a view similar to Fig. 6 with the yarn finger constructed in accordance with this invention in the position shown in Fig. 4; and

Fig. 8 is a view in side elevation of a cam for operating the yarn finger.

In the drawing the invention is shown applied to a yarn finger of a Scott & Williams circular knitting machine such as is shown in the patent to Scott No. 1,152,850, issued September 7, 1915, the yarn finger to which the invention is shown applied being the finger for furnishing reinforcing or splicing yarn for reinforced soles or high splices and the needles to which the reinforcing yarn is fed being shown as raised higher than the other needles when passing the finger feeding the reinforcing yarn. The means for raising these needles may be such as is shown in the patent to Trudel and Dawson, No. 1,775,333, issued September 9, 1930.

In feeding reinforcing yarn to the needles, particularly in machines where additional yarns are fed to the needles for plating, it has been found that where the yarn finger closely approaches the needles the reinforcing yarn is not uniformly on the inside of the fabric. It has also been found that where the yarn finger feeding the reinforcing yarn is shortened so as to feed the reinforcing yarn at such an angle to the needles that it will lie uniformly on the inside of the fabric the yarn finger is too short to properly introduce the yarn to the needles, particularly where the cutter and clamping mechanism used is positioned as in the patent to Page, No. 1,919,123, issued July 18, 1933, as the angle which the yarn makes with the needles when it is held by the clamping mechanism is such that the yarn is not taken by the needles.

In order to obviate the above difficulties the yarn finger F^1 for the reinforcing or splicing yarn which is placed in the usual position with respect to the yarn fingers F^2 , F^3 , F^4 , F^5 for the body and plating yarns is slotted, as at 10, so it may be moved longitudinally as well as pivotally on the pin 12 which supports it, the pin 12 being mounted as usual in the latch guard ring 550. Adjacent the yarn finger F^1 is a plate 14 pivotally mounted on the pin 12 and provided with a slot 16 which receives a pin 18 mounted in the yarn finger F^1 , the head of the pin 18 projecting beyond the plate 14 in position to be engaged by the lever or arm 20, also pivotally mounted on the pin 12. Plate 14 and lever arm 20 are provided with projections 14a and 20a respectively slotted 50 to receive the ends of springs 22, the other ends of which are connected to brackets 24 supported from the latch guard ring. The lever arm 20 is also provided with a raised laterally projecting portion 26 in which is mounted an adjustable 55

stop 28, the portion 26 being positioned so as to place the adjustable stop 28 over the latch ring 550 and the stop 28 being adjusted to determine the lowermost position of the lever arm 20.

- 5 To operate the yarn finger F¹ there is provided a push rod 460 which engages the lower curved edge of the plate 14 and is operated by an auxiliary drum 30 mounted on the main drive shaft 32 or other shaft which rotates synchronously 10 with the needle cylinder so that the push rod 460 is raised and lowered during each revolution of the needle cylinder when the push rod is in engagement with the drum 30. As shown in Fig. 8, the drum 30 is provided with contact 15 portions 30^a and 30^b at different distances radially from the axis of the drum so as to hold the push rod at different vertical positions. In the position shown in Fig. 8 the push rod 460 is moved to its highest position causing the 20 plate 14 to be raised and through engagement of the pin 18 in the slot 16 and beneath the arm 20 raising the yarn finger F¹ and the lever arm 20 upwardly to the position shown in Fig. 5 against the action of the springs 22. As the push 25 rod 460 passes over the contact portion 30^c from the higher contact portion to the lower contact portion the push rod 460 is brought down, as by a spring, (not shown) permitting spring 22 to lower the plate 14. The lever arm 20 is also 30 returned by its spring 22 and through its engagement with the pin 18 brings down the yarn finger F¹ simultaneously with the movement of the plate 14, the yarn finger at that time taking the position as shown in Figure 3, closely adjacent 35 to the needles. The operation of the push rod 460 is timed to bring the yarn finger to that position slightly in advance of the arrival of the first of the high needles which take the reinforcing yarn in each course. As the reinforcing 40 yarn is taken the push rod 460 completes its movement to the low contact portion 30^b on the drum permitting the plate 14 to move downwardly below the position shown in Figure 3 under the influence of its spring 22. As the plate 14 moves 45 downwardly the engagement of the pin 18 in the slot 16 of the plate 14 causes the yarn finger F¹ to be moved longitudinally away from the needles, that is, from the position shown in Figure 3 to the position shown in Figure 4 in 50 which the reinforcing yarn is fed from the corner of the throat plate 559, the slot 10 in the yarn finger F¹ being of sufficient length to permit this movement. As the yarn finger F¹ is lowered to rest upon the throat plate 559 the adjustable stop 28 bears upon the latch guard ring 550 and the lever 20 engages the head of the pin 18 but does not bear thereon so there is no interference with the longitudinal movement of the yarn finger F¹. 55
- 60 As the drum 30 rotates and the push rod 460 moves over the contact portion 30^d between the low and high contact portions 30^b and 30^a of the drum 30 the plate 14 is moved upwardly and through the engagement of the pin 18 in the slot 16 moves the yarn finger F¹ forward towards the needles, the lever arm 20 under the influence of spring 22 preventing any upward movement of the yarn finger F¹ until the pin 18 reaches the lower end of the slot 16. Further movement of the push rod 460 onto the high contact portion 30^a of the drum 30 raises the plate 14 to the position shown in Figure 5, carrying with it the yarn guide F¹ and the lever arm 20. The contact 65 portions 30^c and 30^d of the drum 30 may be

shaped to give the plate 14 movement at the desired rate and in lifting the plate 14 to raise the yarn finger F¹ the contact portion 30^d may be shaped so as to move the yarn finger F¹ only partially towards the needles at the time 5 the last raised needle takes the reinforcing yarn in each course thereby ensuring the withdrawing of the yarn at a predetermined needle and a clean edge to the reinforced section of the stocking, the further movement of the drum moving 10 the yarn finger the remaining portion of its movement outwardly and then pivoting it about the pin 12.

To hold the yarn finger F¹ out of operative 15 position during the knitting of those portions of the stocking where the reinforcing yarn is not used the push rod 460 may be operated from the main drum of the machine to raise the plate 14 and the yarn finger F¹ in the same manner as the push rods are controlled in the patent to 20 Page, No. 1,627,337, issued May 3, 1927.

What is claimed is:—

1. In a knitting machine, a yarn finger for feeding yarn to the needles, means supporting 25 said finger for pivotal and longitudinal movement and means for operating said yarn finger about its pivot in each of a plurality of successive courses to present a yarn closely adjacent to the needles and then shifting said yarn finger bodily away from the needles to a position 30 for feeding the yarn.

2. In a knitting machine, a yarn finger for feeding yarn to the needles, means supporting said finger for pivotal and longitudinal movement and means for operating said yarn finger, said means shifting said yarn finger bodily towards 35 the needles and then operating said yarn finger about its pivot to withdraw the yarn from the needles in each of a plurality of successive courses.

3. In a knitting machine, a yarn finger for feeding yarn to the needles, said yarn finger being 40 mounted for pivotal and longitudinal movement and means for first operating said yarn finger pivotally to a position closely adjacent the needles to present the yarn to the needles and then longitudinally to place the yarn finger in feeding 45 position in each of a plurality of successive courses.

4. In a knitting machine, a yarn finger for feeding yarn to the needles, said yarn finger 50 being mounted for pivotal and longitudinal movement, and means for first operating said yarn finger pivotally to a position closely adjacent the needles to present the yarn to the needles and then longitudinally away from the needles to 55 place the yarn finger in feeding position in each of a plurality of successive courses.

5. In a knitting machine, a yarn finger for feeding a body yarn to the needles, a pivotally mounted yarn finger for feeding a splicing yarn 60 to the needles and means for operating said yarn finger, said means operating said yarn finger about its pivot to present the yarn to the needles and shifting said yarn finger bodily from the needles to feed the splicing yarn in uniform plat- 65 ing relation to the body yarn.

6. In a knitting machine, a yarn finger for feeding yarn to the needles, a support about which said finger pivots, said finger being slotted longitudinally to receive said support, a plate pivotally mounted on said support, a pin and slot connection between said plate and finger and means for operating said plate, said finger being shifted longitudinally upon movement of said plate relatively to said finger. 70 75

7. In a knitting machine, a yarn finger for feeding yarn to the needles, means supporting said finger for longitudinal movement to and from the needles, a pivotally mounted plate, means for operating said plate and a pin and slot connection between said finger and plate for shifting said finger longitudinally upon movement of said plate relatively to said finger.
8. In a knitting machine, a yarn finger for feeding yarn to the needles, means supporting said finger for movement to and from the needles, a pivotally mounted plate, means for operating said plate, a pin and slot connection between said finger and plate for shifting said finger relatively to the needles upon movement of said plate relatively to said finger and means preventing pivotal movement of said finger during movement of said plate relatively to said finger.
9. In a knitting machine, a yarn finger for feeding yarn to the needles, means supporting said finger for movement to and from the needles, a pivotally mounted plate having a slot, means for operating said plate, a pin on said finger engaging in the slot in said plate for shifting said

finger relatively to the needles upon movement of said plate relatively to said finger and means engaging said pin and preventing pivotal movement of said finger during movement of said plate relatively to said finger.

5

10. In a knitting machine, a pivotally mounted yarn finger for feeding yarn to the needles, and means for operating said yarn finger about its pivot to raise and lower said yarn finger in each of a plurality of successive courses, said yarn 10 finger operating means shifting said yarn finger longitudinally toward the needles before the yarn finger is raised and longitudinally away from the needles after the yarn finger is lowered.

11. In a knitting machine, a yarn finger for 15 feeding yarn to the needles, means supporting said finger for pivotal and longitudinal movement and means for operating said yarn finger about its pivot in each of a plurality of successive courses to present a yarn to the needles and 20 then shifting said yarn finger longitudinally to feed the yarn while at a greater distance from the needles.

IVAN W. GROTHEY.

CERTIFICATE OF CORRECTION.

Patent No. 2,051,701.

August 18, 1936.

IVAN W. GROTHEY.

It is hereby certified that error appears in the printed specification of the above numbered patent requiring correction as follows: Page 2, second column, line 66, claim 5, after "yarn" insert the words in each of a plurality of successive courses; and that the said Letters Patent should be read with this correction therein that the same may conform to the record of the case in the Patent Office.

Signed and sealed this 29th day of September, A. D. 1936.

Henry Van Arsdale
